CLOSURE

Philip Gordon Coleman, Cincinnati, Ohio, assignor of one-fourth to Robert Troxel, Cincinnati, Ohio

Application July 8, 1943, Serial No. 493,806

8 Claims. (Cl. 215—98)

My invention relates to improvements in closures and has to do, more particularly, with a closure of such a nature that the elements, of which it is composed, must be adjusted into a predetermined relation to each other before the closure can be applied to or removed from the part which receives it.

The principal object of my invention is to provide a closure, of simple and inexpensive construction, which requires that the parts of the closure be placed in a predetermined relation to each other before the closure can be applied to or removed from a container or the like, by rotative force applied to exposed portions of the closure.

A further object of my invention is to provide a closure comprising a plurality of members rotatable about a common axis and connected by a driving element, which is shiftable, when the members occupy a predetermined relation to each other, from a neutral position, in which the members are independently rotatable about said axis, to a driving position, in which rotative force applied to an exposed portion of one of said members will be transmitted through said driving element to another of said members, formed for interlocking engagement with a portion of a container or the like.

One example of a use for a closure constructed in accordance with my invention is for bottles containing poison. It is desirable that such closures should not be readily unscrewed or removed, so that it can be done without giving particular attention to what is being done. I have provided a closure for such bottles which requires the user to adjust the parts of the closure into a certain relation, before rotative force applied to the exposed portion of the closure will be effective to remove it from the bottle. Thus, the user will be required to give thought and attention to the act of removing the closure, rendering it unlikely that he will take poison from the bottle by mistake, since the care required to remove the closure calls his attention to the nature of the bottle.

Another use for my invention is as a closure for containers, such as outside fuel tanks, to prevent unauthorized access to the contents thereof. It will be necessary to adjust the parts of this closure into predetermined relation to each other before the closure can be removed, and the particular relation, which permits removal of the closure, can be kept as a secret by those entitled to have access to the container.

Further objects, and objects relating to details

of construction and economies of operation, will definitely appear from the detailed description to follow. In one instance, I have accomplished the objects of my invention by the devices and means described in the following specification. My invention is clearly defined and pointed out in the appended claims.

Closures constituting preferred embodiments of my invention are illustrated in the accompanying drawings, forming a part of this specification, in which

Fig. 1 is a perspective view of a bottle having a closure constructed in accordance with my invention applied thereto.

Fig. 2 is a vertical, sectional view through the neck of the bottle and the closure, the parts being in the relation shown in Figs. 1 and 3.

Fig. 3 is a top plan view of the closure, taken on the line 3—3 of Fig. 2, the driving pin being shown in the neutral position.

Fig. 4 is a view corresponding to Fig. 3, but showing the outer closure member adjusted on the inner member to the predetermined position and the pin shifted to driving position.

Fig. 5 is a vertical, sectional view taken on the line 5—5 of Fig. 4.

Fig. 6 is a perspective view of the outer closure member.

Fig. 7 is a perspective view of the inner closure member.

Fig. 8 is a top plan view of a modified form of my invention, suitable for use as a closure for the filler pipe of an outside fuel tank, for instance.

Fig. 9 is a vertical, sectional view, taken on the line 9—9 of Fig. 8.

Fig. 10 is a view corresponding to Fig. 8, the driving pin being shown in section, but with the parts adjusted for removing the closure and the driving pin shifted to the position in which it is effective to transmit rotative force from one of the closure members to the others.

Fig. 11 is a vertical, sectional view, taken on the line 11—11 of Fig. 10.

Fig. 12 is a top plan view of one of the members of the closure.

Fig. 13 is a top plan view of another member of the closure, within which the member shown in Fig. 12 is nested, and

Fig. 14 is a top plan view of a third member of the closure, which is nested within the member shown in Fig. 13.

In the drawings, the same reference numerals refer to the same parts throughout the several views and the sectional views are taken looking in

the direction of the arrows at the ends of the section lines.

In general, my invention consists of a closure which comprises a plurality of members rotatable about a common axis. One of these members is formed for interlocking engagement by rotative movement with a portion of a container or the like. Means are provided, operable only when these members occupy a predetermined relation to each other, for transmitting rotative force to the member which is formed for interlocking engagement. One way of accomplishing this is to provide each of the members forming the closure with a slot, one end of which is concentric with the axis about which the closure members are rotatable, and to provide a driving pin which extends through these slots and is shiftable therein, when the closure members are adjusted so that the slots are in alignment. When this driving pin occupies the ends of the slots that are concentric with the axis of rotation, the closure members are independently rotatable about the pin, but, when it is shifted to the other ends of the slots, a rotative force applied to an exposed portion of one of these members will be transmitted by said pin to the other members, one of which may have an interlocking engagement with a portion of the container. Since the closure members have to be adjusted into predetermined relation with each other, before the driving element can be shifted to effective position, it is desirable to provide means for indicating the relative positioning of said members. This may be done in various ways, such as, by providing a spot on one of the members to be lined up with a hole in another, or by providing numbers or characters on the closure members which have to be lined up in a certain relation before the driving element can be shifted from neutral to effective position.

Referring to the numbered parts of the drawings, I have shown, in Fig. 1, a bottle 10 having a neck 11, formed with external screw threads 12. The closure comprises an inner member 13, having a flange 14 depending from the top thereof and provided with internal threads 15, for screw engagement with the neck of the bottle. A slot 16 is formed in the top of the member 13 and so located that one end of the slot is concentric with the axis about which the member 13 rotates. The closure includes an outer member 17, having a flange 19 depending from the top thereof, and the top of member 17 is also provided with a slot 18, one end of said slot being concentric with the axis about which member 17 rotates and both members 13 and 17 being rotatable about a common axis. A driving pin 20 extends through the slots 16 and 18, having a head 21 on its lower end engaging the undersurface of member 13, and a head 22 on its upper end engaging the upper surface of member 17. If desired, the head 22 may be made large enough to form an operating handle or button and to cover the slot 18 completely. A sealing disc 23 is inserted within the closure member 13 and fits against the undersurface of the top thereof, covering the slot 16.

It will be observed that the closure member 17 fits over the closure member 13 and embraces it, substantially concealing the latter, with the result that the user has to apply the rotative force for screwing on or unscrewing the closure to the outer member 17. When the two members are in the position shown in Figs. 2 and 3, the outer member 17 is rotatable with respect

5 to member 13 and, consequently, a rotative force applied to member 17 will be ineffective to rotate member 13. However, if member 17 be rotated with respect to member 13 until the slots 18 and 16 are in alignment, the driving pin 20 may be shifted from the ends of these slots concentric with the axis of rotation to the opposite ends thereof and, when the driving pin is thus positioned eccentrically, a rotative force applied to the outer member 17 will be transmitted by the driving pin 20 and the walls of the slots 18 and 16 to the inner member 13, so as to screw it on or unscrew it from the neck of the bottle.

10 Members 13 and 17 have to be relatively positioned so that the slots 16 and 18 are aligned, before the driving pin 20 can be shifted from the neutral or concentric position to the driving or eccentric position, and it is desirable to provide means for indicating this relative positioning of the closure members. To that end, I provide upon the upper surface of the closure member 13 a spot 15 24 of distinctive color and, in the top of the closure member 17, a hole 25 through which the spot may be exposed. When member 17 is adjusted with respect to member 13 until the spot 24 shows through the hole 25, the slots 18 and 16 will be aligned and the pin 20 can be shifted to the driving position.

15 The embodiment of my invention just described constitutes a simple form of closure that cannot be unscrewed from a bottle by a simple mechanical act, but requires thought and attention in that the user must first rotate the outer member 17 until the spot 24 is visible through the opening 25 and, then, shift the pin 20 from the concentric to the eccentric position, after which the closure may be unscrewed by rotative force applied to the flange 19 of the member 17. I believe that this form of my invention will find utility as a closure for bottles containing poison, for instance, in that it would be impossible for a user to remove the closure from the neck of the bottle and take the poison by mistake. The very fact that it is necessary to adjust the closure members to a predetermined position, and then shift the driving pin, before unscrewing the closure is an indication to the user that he is not opening an ordinary bottle, but one containing poison. It may well be the case that the mental concentration, necessary to adjust the parts of this closure to the position in which it can be removed, would be sufficient to divert the attention of one contemplating suicide from his troubles and thus prevent his taking the poison deliberately.

20 In Figs. 8 to 14, inclusive, I have shown an embodiment of my invention particularly useful as a closure for containers, such as outside fuel tanks, for the purpose of preventing unauthorized access to said containers. In Figs. 9 and 11, the filler pipe of such container is indicated at 26, being internally threaded at 27. A disc-like member 28 has an upstanding peripheral flange 30, which is externally threaded at 29 for engagement with the threads 27 of the filler pipe. The disc-like member 28 has a slot 31 therein, one end of which is concentric with the axis of rotation of said member. Mounted above the member 28, and nested within the flange 30, is a disc 32 having an upstanding peripheral flange 33 from the upper end of which there extends laterally an annular flange 34, of sufficient width to extend over the flange 30 of member 28, and over the upper end of the filler pipe 26. Member 32, also, has a slot 35 therein, one end of which 25 is concentric with the axis about which the mem-

ber 32 is rotatable. Mounted above the member 32 and nested within the flange 33 is a disc 36, having an upstanding peripheral flange 37. The disc 36, also, has a slot 38 therein, one end of which is concentric with the axis about which the disc 36 is rotatable. Mounted above the disc 36, and nested within the flange 37 thereof, is a member 39 provided with an upwardly extending boss 40 that is square in cross-section, so that a wrench may be applied thereto for rotating the member 39. A slot 41 is provided, which extends through the member 39 and boss 40, and one end of said slot is concentric with the axis about which member 39 is rotatable.

A driving pin 42 extends through the slots 31, 35, 38 and 41 and is provided with a head 43, engaging the lower surface of the member 28, and a head 44, engaging the top of the boss 40. The head 44 may be made large enough to furnish a convenient button for shifting the driving pin, and to cover the upper end of the slot 41. A sealing disc 45 may be applied to the lower surface of member 28 to cover the head 43 of the driving pin and the slot 31. When the pin 42 is located in the ends of the slots 31, 35, 38 and 41 that are concentric with the common axis about which the members 28, 32, 36 and 39 are rotatable, said members are independently rotatable about said pin. However, if the members be adjusted until all of the slots are in alignment, and the pin 42 be then shifted into the other end of said slots, that is, the ends opposite those that are concentric with the common axis, the application of rotative force to member 39, as by means of a wrench applied to the boss 40, will be transmitted by the pin 42 and the walls of the slots 41, 38, 35 and 31 to the member 28 to unscrew said member from the filler pipe 26, or to screw it into engagement therewith. It will be observed that this requires that four slots be brought into alignment with each other, before the pin 42 can be shifted to the eccentric or driving position.

Since it is necessary to adjust or position the members 28, 32, 36 and 39 relative to each other, to bring the slots into alignment, it is desirable to provide means for indicating the relative positioning of said members. To that end, I mark the numbers "1" to "8," inclusive, as at 47, upon the upper surface of the flange 30 of the member 29. I provide, in the flange 34 of the member 32, an opening 48 so positioned that the numbers, indicated at 47, may be visible through said opening. Upon the upper surface of the flange 37 of member 36, I have marked the numbers "1" to "8," inclusive, as at 49, and I have provided an upstanding lug 50 by means of which the member 36 may be rotatably adjusted. Upon the disc-like portion of the member 39, I have marked the numbers "1" to "8," inclusive, as indicated at 51. The relative positioning of the closure members may be indicated by these numbers. Thus, as illustrated, when the number "2" on flange 30 of member 28 is in line with the hole 48 in flange 34 of member 32, the number "1" on flange 37 of member 36 in line radially with this hole, and the number "6" upon the upper surface of member 39 in line with the number "1" and the hole 48, the members 28, 32, 36 and 39 are so positioned that the slots 31, 35, 38 and 41 are in alignment, so that the driving pin 42 can be shifted from its concentric or neutral position to its eccentric or driving position. In other words, the combination indicating the posi-

tioning of the parts which permits the pin to be shifted to driving position, is "216."

It will be evident that this embodiment of my invention constitutes a relatively inexpensive and simple closure, suitable for use for containers such as outside fuel tanks and the like, and which will prevent access to such containers by unauthorized persons, but which can quickly be set by an authorized person, who knows the combination, to such position that the closure may be readily removed.

I am aware that the structures illustrated herein as embodiments of my invention are susceptible of considerable variation without departing from the spirit of my invention and, therefore, I claim my invention broadly as indicated in the appended claims.

What I claim is:

1. A closure comprising the combination of a plurality of members rotatable about a common axis, and each having a radial slot therein one end of which is concentric with said axis; a driving element extending through said slots and shiftable therein when said slots are aligned, one of said members being threaded for screw engagement with a portion of a container and rotatable by force applied to another of said members, when said element is shifted from the ends of said slots that are concentric with the axis of rotation and means for preventing access to said first member.

2. A closure comprising the combination of a rotatable inner member having a depending flange, internally threaded for screw engagement with a portion of a container, and a top having a slot therein, one end of which is concentric with the axis of rotation of said member; an outer member rotatable about said inner member and embracing and substantially concealing the same, said outer member having a depending flange and a top with a slot therein, one end of which is concentric with the axis of rotation of said outer member; a pin, headed on both ends, extending through said slot; and means for indicating the relative positioning of said members with said slots in alignment.

3. A closure comprising the combination of a rotatable inner member having a top and a flange, internally threaded for screw engagement with a portion of a container, said top having a slot therein one end of which is concentric with the axis of rotation of said member; an outer member rotatable about said inner member and embracing and substantially concealing the same, said outer member having a flange and a top with a slot therein, one end of said slot being concentric with the axis of rotation of the outer member; a pin, headed on both ends, extending through said slots; a sealing disc fitted within the inner member and covering the slot therein; and means for indicating the relative positioning of said members with said slots in alignment.

4. A closure comprising the combination of a rotatable inner member having a top and a flange, internally threaded for screw engagement with a portion of a container, said top having a slot therein, one end of which is concentric with the axis of rotation of said member; an outer member rotatable about said inner member and embracing and substantially concealing the same, said outer member having a top and a flange, said top having a slot therein one end of which is concentric with the axis of rotation of the outer member; and a pin extending through both slots and having heads on both ends thereof, the top of said inner member having a spot thereon of dis-

tinctive color and the top of said outer member having a hole therein, so located that said spot is disclosed therethrough when the members are so positioned relative to each other that the slots are aligned.

5. A closure comprising the combination of a plurality of members rotatable about a common axis, one of said members being formed for interlocking engagement with a portion of a container, another of said members being formed for application of rotative force thereto, each of said members having a radial slot therein one end of which is concentric with said axis; a driving element extending through said slots and shiftable, when said slots are aligned, from a position in the ends thereof concentric with said axis, in which said members are independently rotatable about said element, to a position in the other ends of said slots, in which rotative force applied to one of said members will be transmitted to the others through said element; and means for preventing access to said first member.

6. A closure comprising the combination of a first member threaded for screw engagement with a portion of a container; a second member nesting within the said first member; a third member nesting within said second member; a fourth member nesting within said third member and having a non-circular portion through which rotative force may be applied thereto, all of said members being rotatable about a common axis, each of said members having a slot therein, one end of which is concentric with said axis; a driving pin extending through said slots and shiftable, when said slots are aligned, from a position in the ends thereof concentric with said axis, in which said members are independently rotatable about the pin, to a position at the opposite ends of said slots, in which the pin transmits rotative force

from the fourth member to the first member; and means for indicating the relative positioning of said members in which all said slots are aligned.

7. A closure comprising the combination of a first member threaded for screw engagement with a portion of a container, and having indicia on an upper surface thereof; a second member nested within said first member, and having a flange projecting over said surface and provided with an opening through which said indicia may be exposed; a third member nested within said second member, and having indicia on an upper surface thereof; a fourth member nested within said third member, having indicia on an upper surface thereof and a non-circular portion through which rotative force may be applied thereto, all of said members being rotatable about a common axis, and each having a slot therein one end of which is concentric with said axis; and a pin, headed on both ends, extending through said slots and shiftable, when said members are in predetermined relation to each other, from the ends of said slots concentric with said axis to the opposite ends thereof, whereby rotative force applied to said fourth member will be transmitted through said pin to said first member.

8. A closure comprising the combination of a plurality of members rotatable about a common axis, one of said members being formed for interlocking engagement by rotative movement with a portion of a container; and means accessible from the exterior of the closure and shiftable, when said members are in predetermined relation to each other, from a position coaxial with said members to an eccentric position in which it transmits rotative force to said first-mentioned member from another of said members.

PHILIP GORDON COLEMAN.
